UNITED STATES PATENT OFFICE.

HENRY HANDY, OF NEW YORK, N. Y.

DESIGN FOR A CRACKER OR LIKE ARTICLE.

45,152.

Specification for Design.

Patented Jan. 13, 1914.

Application filed October 17, 1913. Serial No. 795,786. Term of patent 7 years.

To all whom it may concern:

Be it known that I, HENRY HANDY, a citizen of the United States, and a resident of the city of New York, borough of Manhattan, in the county and State of New York, have invented a new, original, and ornamental Design for Crackers or like Articles, of which the following is a specification, reference being had to the accompanying drawing, forming part thereof.

The figure is a perspective view of a cracker or like article showing my new design.

I claim:

The ornamental design for a cracker or like article, as shown.

HENRY HANDY.

Witnesses:

THEO. G. HOSTER,
PHILIP D. ROLLHAUS.
